HARVEY CLAYTON RENTSCHLER AND JOHN WESLEY MARDEN, OF EAST ORANGE,
NEW JERSEY, ASSIGNEES TO WESTINGHOUSE LAMP COMPANY, A CORPORATION
OF PENNSYLVANIA.

FURNACE.

Application filed July 28, 1921. Serial No. 488,230.

Our invention relates to metallurgical furnaces and more particularly to electrical furnaces in which the material undergoing treatment assists in the operation of the furnace.

The subject matter of this invention is also disclosed but not claimed in an application filed by us, Serial No. 488,229, filed July 28, 1921, on a process of manufacturing metals and their uses, and assigned to the same assignee as the present invention.

An object of our invention is to provide a furnace in which metallic and semi-metallic substances, which cannot at present be satisfactorily worked, may be heat treated to render them workable.

A further object is to provide a vacuum electrical furnace in which the material being treated is adapted to complete the electrical circuit.

Another object is to provide a vacuum electrical furnace of simple design and economical construction.

Other objects will be apparent from a reading of the following description.

In making a series of experiments with the view of devising a satisfactory mode of treatment whereby certain substances, such as tungsten, molybdenum, chromium, zirconium, thorium, titanium, uranium, vanadium, tantalum, beryllium, etc., may be altered to such an extent that they may become malleable or even rendered ductile, we have devised a special type of furnace for use in connection therewith and which may prove generally useful in conducting metallurgical treatments of various natures.

The furnace or treating vessel we have devised operates on a different principle from any other of which we are aware, in that the material being heat treated is maintained in the highest attainable vacuum during the treatment. Briefly stated, the furnace comprises a closed treating vessel or envelope which may be termed a treating bottle. The bottle may be made of any suitable material, but we prefer to employ a non-conducting material, such as hard glass, which is capable of withstanding high temperatures. The bottle is hermetically sealed during the heat treatment operation and has provision for facilitating the maintenance of a high vacuum therein during

such treatment. The material undergoing treatment is supported within the container by means of water-cooled spring clamps, one of which is connected to a terminal or electrode suitably connected to an outside source of electrical energy, while the other dips into a water-cooled pool of mercury to such depth as to insure contact therewith as the stick shortens during the heat treatment. The pool of mercury, through a conductive contact, is connected to the source of energy aforementioned, thus completing the electrical circuit.

Referring now to the view shown in the accompanying drawing, the embodiment of our invention illustrated thereby comprises a globular envelope or container 1 having two diametrically opposed necks 2 and 3 which have flared recesses or openings 4 and 5 therein communicating with the interior of the envelope. The envelope may be made of any suitable material which will maintain a vacuum created therein. We prefer, however, as mentioned above, to employ a hard glass capable of withstanding the range of temperatures to which the material undergoing treatment may be subjected. This envelope forms the main body of the treating vessel or bottle and may be of any desired size.

Positioned intermediate the two necks 2 and 3, and preferably slightly closer to the neck 2, is a tube 6 which communicates with the interior of the vessel. This tube furnishes a convenient means for connecting the vessel to a diffusion pump (not shown) in order that a vacuum of high degree may be maintained within the vessel when the openings 4 and 5 are hermetically sealed.

In order to hermetically seal the envelope against the entrance of any deleterious matter, we prefer to provide each of the openings with stoppers or electrodes, termed terminals, 7 and 8. Any desirable material or style of stopper which will serve the purpose of conducting an electrical current to the interior of the vessel may be employed. However, we have made use of iron stoppers having chambers 9 and 11 therein for a purpose to be later described. The stoppers should have a ground fit within the necks 2 and 3 and be slightly tapered inwardly to make a tighter fit. Liquid cement or any

other desired material may be employed to make the joint between these stoppers and the walls of the vessel gas-tight. We have found, however, that a carefully ground joint forms a hermetic seal.

The stoppers preferably have hollow nipples 12 and 13 which project within the vessel in order to bring the material undergoing treatment well within the vessel.

10 Fitted within the chambers are covers 14 and 15 for the openings thereto, and fastened within two openings in these covers or closures, are two pairs of pipes 16, 17, 18 and 19, the pipes 16 and 18 projecting but 15 slightly within the chambers while the pipes 17 and 19 reach well down within the nipples. Circulation of the cooling medium to prevent overheating of the iron stoppers or electrodes may be had by appropriate connection to the pipes from a suitable circulating device (not shown).

The stoppers are identical in structure with the exception that the upper stopper 7 may be provided with a clamping means 23 of any desirable structure by means of which the material undergoing treatment may be firmly secured in depending position within the container. We have employed a spring clamp 21 comprising a bolt 22 slidably engaging an opening 23 in an extension 24 of the electrode 7. The bolt has two heads 25 and 26, the former engaging an abutment 27 of the stopper 7 and the latter preventing disengagement of the bolt from its support. A spring 28 maintains the head of the bolt in firm engagement with the abutment 27 so that material positioned therebetween will be rigidly held in proper position within the vessel. The 40 spring clamp provides a convenient means for facilitating the insertion and removal of the material.

Contact between the lower stopper or electrode and the material supported by the upper electrode may be maintained by a pool 45 of mercury or other conducting material surrounding the lower electrode and a spring clamp 29 secured to the lower end of the material being treated. The clamp 50 29 is of such length that when the material shortens or shrinks, a continuous circuit will be maintained between the two electrodes.

An electrical current may be conducted to the device from any appropriate source 55 of electrical energy (not shown) by means of the conducting wires 31 and 32 which may be suitably clamped to the stoppers or electrodes by means of clamps 33 and 34.

The operation is as follows: Material 60 such as sintered tungsten, molybdenum, chromium, zirconium, thorium, titanium, uranium, vanadium, tantalum, beryllium, etc., is clamped to the electrode 7 by means of the clamp 21. The spring clip 29 is placed 65 over the lower end, thus ensuring a firm

contact. The stopper 7 is then sealed into the opening 4, after which the diffusion pump is operated until a high vacuum is produced within the vessel. Thereafter, the current is admitted to the material gradually and is increased until the value thereof is 80 or 90%, more or less, of the fusion current. This current is maintained until the material is properly conditioned so that, thereafter, further mechanical treatment 70 thereof will render it ductile. After the material has been heat-treated until it may be wrought, the current is reduced gradually to zero and the material removed. By fusion current, we mean that value of current required to melt off the bar when undergoing treatment.

It will be understood that many modifications of the above described apparatus may be made without departing from the 85 spirit of our invention.

What is claimed is:

1. A device for heat-treating material, comprising an enclosing envelope having a plurality of openings, closures comprising 90 electrodes fitted in the openings, a pool of electrically conductive liquid within said envelope and in which one of said electrodes is immersed, and means mounted on the other electrode for engaging the material to be heat-treated.

2. A device for heat-treating material comprising an enclosing envelope having outwardly extending oppositely disposed necks, closures for said necks, said closures 100 constituting electrodes, a pool of electrically conductive liquid in said envelope and in which one of the electrodes is immersed, and means supported by the other electrode for pendently supporting the material to be 105 heat-treated.

3. A device for heat-treating material, comprising an enclosing envelope having a plurality of openings, stoppers constituting electrodes for the openings, a pool of mercury immersing one of said electrodes, means carried by the other electrode for pendently supporting the material to be 110 heat-treated, and means for cooling said stoppers.

4. A device for heat-treating material, comprising an enclosing envelope, a plurality of removable electrodes in said envelope, a pool of mercury enveloping the inner end of one of said electrodes, means carried by the other electrode for supporting the material to be heat-treated, and means for maintaining an electrical circuit between said mercury pool and an electrode through 120 the material being heated when the latter shrinks.

5. A heat-treating apparatus comprising a container having a plurality of openings, a conductive liquid in said container, a plurality of removal closures for the openings 125

- in said container, one of said closures having its inner end immersed in said liquid, said closures constituting electrodes, means carried by one of said electrodes for securing thereto materials to be treated, means for maintaining contact between the material and the conductive liquid, and means for exhausting said container.
- 10 6. A heat-treating apparatus comprising a container having oppositely disposed openings therein, a hollow electrically conductive closure for each of the openings, means for circulating a cooling fluid within
- 15 said closures, a conductive liquid pool, immersing the inner end of one of said closures, means carried by the other closure for supporting the material to be heated, means for maintaining the material in electrical
- 20 circuit with said conducting liquid during heating, and means for exhausting said container.
7. A treatment bottle comprising a vessel of hard glass having three openings therein, stoppers of conducting material sealed 25 gas-tight in two of said openings, and a tube connected to the remaining opening, means connected to said tube for evacuating the air and occluded gases from said vessel, means connected to said stoppers for passing an electric current therethrough when the material undergoing treatment is placed in circuit therewith and means for cooling said stoppers.
- In testimony whereof, we have hereunto 30 subscribed our names this 27th day of July 1921.

HARVEY CLAYTON RENTSCHLER.
JOHN WESLEY MARDEN.
